UNITED STATES PATENT OFFICE.

FREDERICK SIMMONS, OF LONDON, COUNTY OF SURREY, ENGLAND, ASSIGNOR,
BY MESNE ASSIGNMENT, TO THE UNITED STATES AUTOMATIC BUTTON
HOLE SEWING MACHINE COMPANY.

BUTTON-HOLE SEWING-MACHINE.

SPECIFICATION forming part of Letters Patent No. 249,411, dated November 8, 1881.

Application filed July 19, 1881. (Model.)

To all whom it may concern:

Be it known that I, FREDERICK SIMMONS, a subject of the Queen of Great Britain and Ireland, and a resident of London, in the county of Surrey, England, have invented certain new and useful Improvements in Button-Hole Sewing-Machines, of which the following is a specification.

My invention relates to that class of button-hole sewing-machines in which the cloth is held in a clamp having an intermittent lateral reciprocating motion imparted to it to enable the needle to produce the overseam or button-hole stitch, and also an intermittent feed motion at right angles to the other in the direction of the length of the button-hole; and my present invention relates more particularly to certain improvements in the machine of this class for which Letters Patent of the United States were granted to me June 24, 1879, No. 216,902.

The object of my invention is to improve and simplify the construction of the devices for controlling and limiting the movement of the clamp and its slides, as more fully described hereinafter.

In the accompanying drawings, Figure 1 is a plan view of my improved machine; Fig. 2, a rear elevation. Fig. 3 is a vertical sectional view on the line $\alpha\alpha$, Fig. 1; Fig. 4, an inverted plan view of a portion of the machine, showing the let-off motion and clamp-slides; and Fig. 5 is a detached perspective view of the mechanism for controlling and limiting the reciprocating stitch-forming movement of the slides carrying the cloth-clamp.

The general principles of this machine are the same as those of the machine for which I obtained the above-mentioned patent, the present improvements relating only to modifications in the details of construction.

The sewing mechanism may be precisely the same as that described in said patent, and is so shown in the drawings, and consists of a needle carried by a vertically-reciprocating slide, a , Fig. 1, adapted to guides in the head of the machine, and a horizontally-reciprocating shuttle, b , both having the necessary reciprocating motions imparted to them through 50 suitable levers by grooved cams on the driv-

ing-shaft A of the machine, as shown in my said patent.

The lower part of the cloth-clamp is enlarged in the form of a horizontal traversing table, G^4 , while the upper part, M , of the clamp consists of a slotted concave plate pivoted in the forked lower end of a vertical stem, m , as in my patent above cited, this stem being adapted to the outer end of a curved arm, M' , carried by the table G^4 . A spiral spring acting on the stem m within the arm tends to keep the upper part of the clamp raised; but the latter may be depressed to gripe the cloth, and retained by the pivoted catch or yoke m' acting on the head of the stem m .

The clamp-table G^4 is carried by and secured to the upper slide, G^3 , which rests and can slide on the lower or primary slide, G , Figs. 2, 3, and 5, the secondary slide G^3 being guided on the primary slide G by a cylindrical rod, G^2 , secured to the slide G , and passing through an opening in the slide G^3 , Fig. 5, so as to permit an intermittent feed motion to be imparted to the upper slide on the lower one in the direction of the length of the button-hole by the devices hereinafter described. The primary slide G is carried by a horizontal sliding bar or rod, D , adapted to bearings in the upright portions or ribs G' G'' of the frame of the machine. The slide also has a bearing on the top of the centerrib, G' , Figs. 2 and 3. The connection of the primary slide with the rod D is a yielding one, through the medium of the spring let-off devices illustrated in Figs. 2, 3, 4, and 5. The slide G is in the form of an open frame-work, and has two pendent portions, H^4 H^5 , with beveled faces, against which bear the beveled ends of a lever, H , pivoted by means of a screw, H^3 , to the under side of a block, H' , secured by a screw, H^2 , to the rod or bar D . Springs I , secured to the opposite ends of the lever H , bear on the pendent pieces H^4 H^5 of the slide and keep the beveled ends of the lever H in close contact with the said pieces, so that the primary slide, and with it the secondary slide and cloth-clamp, will move with the sliding rod D , except when the movement of the slides is interfered with, in which case full movement will be allowed the rod by the yielding of the springs and the slipping of

the yielding of the springs and the slipping of 90

the yielding of the springs and the slipping of 95

the yielding of the springs and the slipping of 100

the beveled faces on each other, the lever H turning on its pivot against the action of the springs. The end of the bar D away from the slide is bent upward and provided with an anti-friction roller, d, adapted to a cam-groove, B', on the side of a pinion, B, which turns on a stud, C, secured to a fixed part of the frame. This pinion B gears into and is driven by a pinion, A', on the driving-shaft A, so that 5 when the machine is in operation the cam B' will impart to the bar D an intermittent reciprocating motion, which is transmitted to the slides and cloth-clamp through the devices described, the slides and cloth-clamp partaking 10 of the full extent of motion of the bar, except when restricted by the devices hereinafter described, and this movement taking place only when the needle is out of the cloth.

The rocking shaft E of my above-described 20 patent is dispensed with, and the sliding cam is replaced by a rotary cam, which I arrange on the feed-cam shaft in connection with a yoke which is a modification of the hook n of the patent.

25 The feed-cam shaft F of my present machine has an intermittent rotary motion imparted to it through the medium of a clutch, P, operated by an arm, Q, which is acted on by a cam on the driving-shaft A, as in my aforesaid patent. 30 A friction-spring, O, bears on the periphery of the clutch-disk, as shown in Fig. 2. On the shaft F is the cam F', whose groove forms a regular right and left hand screw, and imparts the intermittent feed motion to the upper slide 35 and cloth-clamp. Owing to the differences in the general relation of the parts, the rocking shaft V of the said patent, with its arms U W, is reduced to the form of a simple lever, K, pivoted on a pin, K', on a fixed portion of the frame, and having at one end an anti-friction roller, F'', adapted to the groove of the cam F', and at the other end a slot, K'', in which is adjustably secured by a handled nut, K'', a pin, K'', which projects into a recess or slot, K'', in 40 the table G⁴ of the secondary slide, so that the cam F' will impart through the lever K an intermittent feed motion to the table, upper slide, and cloth-clamp the length of the button-hole, first in one direction and then in the other, 45 and the extent of this movement, and consequently the size of the button-hole, may be varied by adjusting the pin K'' in the slot K'' of the lever to increase or decrease the leverage. 50

The shaft F is provided with a handle, P', 55 so that the secondary slide and cloth-clamp may be adjusted through the medium of the cam F' and lever K to any desired position, as described in said patent, to permit the stitching of the button-hole to be commenced or resumed at any point without operating the stitching mechanism.

On the shaft F, attached to the cam F', or forming part thereof, is a stop-cam, F', having a projecting tappet, F'', and this is embraced 65 by a hook or yoke, E, carried by the tubular bar or arm e, connected by an angle-piece, e',

to a projecting arm on the primary slide G, so that the yoke moves with the slide. The tubular bar or arm e fits over the rod D, so as to be guided thereby, but be capable of an independent longitudinal motion. 70

The yoke E has two internally-projecting segments, E³ E³, of equal size, and between the latter equal recesses E² E². The periphery of the cam F' is cylindrical, with a tappet, F'', 75 having a cylindrical face, both concentric with the axis of rotation of the shaft, and the diameter of the cam through the tappet is less than the distance from face to face of the segments E³ E³, so as to allow the yoke, and consequently the slides and cloth-clamp, the extent of reciprocating motion necessary to form the overseam-stitch for the sides of the button-hole, while the play or extent of movement between the cam and the segments E³ E³, when 80 the tappet F'' lies in one or other of the recesses between the segments, is equal to the length of stitch required to form the bars at the ends of the button-hole.

The operation of the machine will be readily 90 understood from the foregoing description. A laterally-reciprocating motion is imparted to the two slides and the cloth-clamp from the cam B' through the rod D, and at the same time an intermittent feed motion is imparted 95 to the upper slide-table G⁴ and cloth-clamp by the cam F' through the lever K. The stop-cam F', being attached to or forming part of the cam F', always bears such a relation to the latter that when the pin F'' of the lever K is at 100 one or other of the junctions of the right and left hand portions of the groove of the cam F', and the cloth-clamp consequently at one or other end of its feed movement, the tappet F'' lies in the recesses between the segments E³ 105 E³, the movement of the yoke is limited only by that part of the cam other than the tappet, and full movement of the slides and cloth-clamp is allowed to form the long barring 110 stitches at the end of the button-hole; but when the cam moves to the position shown in Fig. 3, for instance, and the feed movement is in progress lengthwise of the button-hole, the tappet F'', coming into contact with the segment E³, restricts the lateral movement of the 115 slides and cloth-clamp, so as to form the short stitches along the side of the button-hole; and, in like manner, when the tappet comes into contact with the segment E³ on the other side, it limits the movement of the cloth-clamp in 120 the other direction, so as to form the short stitches on the other side of the button-hole.

I claim as my invention—

1. In a button-hole sewing-machine, the combination of a cloth-clamp, and slides carrying 125 said clamp, and mechanism, substantially as described, for reciprocating the slides, with an intermittently-rotating stop-cam, and a yoke connected to the clamp and having projecting segmental bearing-surfaces and intervening 130 recesses, substantially as set forth.

2. In a button-hole sewing-machine, the com-

bination of a cloth-clamp, slides therefor, and mechanism for imparting a reciprocating motion thereto, with devices, substantially as described, whereby said movement is restricted, 5 and springs making a yielding connection between the said reciprocating mechanism and the slide, all substantially as described.

3. The combination of a reciprocating bar and a slide operated thereby with a lever pivoted to said bar and having inclined faces to 10 act on inclined surfaces attached to the slide, and springs for retaining the lever in position.

4. In a button-hole sewing-machine, the combination of a cloth-clamp and slides therefor, 15 and reciprocating mechanism having a yielding connection with the slides, with a rotary

stop-cam, and a yoke connected to the clamp and having projecting segmental bearing-surfaces and intervening recesses, all substantially as specified.

5. In a button-hole sewing-machine, the combination of a reciprocating cloth-clamp and slides, with a rotary screw-cam and lever for imparting a feed motion to the clamp, a yoke connected to the slides, and a stop-cam 20 25 embraced by the yoke and formed in one piece with or fixed to the feed-motion screw-cam, substantially as set forth.

F. SIMMONS.
